AUTOMATIC EXTRUSION GRIPPER ASSEMBLY
Kenneth L. Harwood, Arnold F. Ingalls, and Benjamin F. Smith, Grand Rapids, Mich., and William F. Meredith, Youngstown, Ohio, assignors to Light Metals Corporation, Grand Rapids, Mich., a corporation of Michigan
Filed Sept. 23, 1959, Ser. No. 841,801
4 Claims. (Cl. 207—1)

This invention relates generally to material handling apparatus, and more particularly to the use of material handling apparatus with and as a part of metal extruding equipment.

This application is a continuation-in-part of copending application Serial No. 634,014 filed January 14, 1957, entitled "Extrusion Puller" now abandoned.

Metal extruding processes require having a billet of the metal heated to a plastic or semi-plastic state. The billet is then placed in a container located in a press and disposed immediately behind an extrusion die. A hydraulic ram is disposed behind the billet to provide a continuous force which causes the material of the billet to flow through the extrusion die and assume the cross-sectional shape of the die opening. The extruded member or members is of a length dependent upon the size of the billet and the size and number of openings in the extrusion die. In those instances in which members of considerable length are formed, it is conventional to provide a run-out table that extends for a considerable length from the press. Such tables support the extrusions as they are being formed, and are intended to afford free flow of the billet material as it passes through the openings of the extrusion die.

The material received through an extrusion die is in a pliable state and readily subject to deformation. Accordingly, it has long been a practice to provide workers to guide the material as it passes over the run-out table. The workers exert either no pulling force or a slight and steady force on the strip members as they are extruded and flow out over the run-out table. Their purpose is to prevent the extruded strips from buckling or touching other extruded strips and to direct the strips in a straight path. The highly pliable state of the extruded strips causes the members formed to also be subject to deformation due to stretching.

The plastic or pliable state of the extruded members, causing such care to be taken in running them out, has heretofore discouraged manufacturers from using mechanical handling means in place of the workers mentioned. However, the use of manual labor has its limitations also. When several extruded members of considerable length emerge from a single die, more than one or two workers may be required. Aside from the labor cost, the workers often get in each others' way in attempting to allow their extrusions to flow naturally and in keeping them in a straight and free flowing path.

This invention is directed to means for automatically receiving, engaging and directing an extruded work piece, or plurality of work pieces, out over the run-out table as they are being formed and expelled through the extrusion forming die. Such means includes work carriers that travel to and from the extrusion press and which include work grippers for engaging and holding a work piece therein. Further, means of automatic actuation of the work carrying means is incorporated within the work receiving heads thereof, so that the work member itself is instrumental in effecting the start of the run-out operation.

In brief, the material handling apparatus of this invention includes a plurality of overhead guide tracks extending between an extrusion press and a support tower located at the end of the run-out table. Each track guides

2

a separate carrier member. Each carrier member includes its own work receiving head and means of engaging an extruded work member as it is received therein. Each carrier member also includes its own work gripper resetting mechanism. Further, they each make use of a control system interrelated with the gripper and its resetting means to effect their automatic run-out and return travel.

The objects of this invention include disclosing mechanical means of handling extruded work pieces during the metal extrusion process.

Another object of this invention is to disclose a guided work carrier having means of engaging an extruded work piece immediately as it emerges from the extrusion press.

Still another object of this invention is to disclose a work piece gripping mechanism which is actuated by the receipt of a work member therewithin.

A further object of this invention is to disclose a work gripper means which is part of a work carrying device and includes means for automatically signaling the commencement of the carrier operation upon the receipt and engagement of a work member therewithin.

A still further object of this invention is to disclose a mechanism for automatically releasing the work gripping means from engagement with a work piece, and for resetting it for subsequent operation.

Also among the objects of this invention is to provide means for having the gripper resetting mechanism form part of the carrier devices and to be actuated at the end of its travel.

These and other objects of this invention will be more apparent upon a reading of the specification which follows, in conjunction with the accompanying drawings wherein:

FIG. 1 is a side plan view of the extrusion handling apparatus of this invention.

FIG. 2 is an enlarged top elevational plan view of the extrusion handling apparatus of FIG. 1 as seen from the section-line II—II thereof, and looking in the direction of the arrows.

FIG. 3 is an enlarged side plan view of the trolley or carriage and work receiving support frame, of the extrusion handling apparatus, shown at the right in FIG. 1.

FIG. 4 is a further enlarged cross sectional view of the trolley support means including the hanger as seen from the section-line IV—IV in FIG. 3 and looking in the direction of the arrows thereon.

FIG. 5 is a partial perspective view of a die and canister set up.

FIG. 6 is an end cross sectional view taken through the bank of work handling devices of FIG. 3 along the section-line VI—VI thereof, and looking in the direction of the arrows.

FIG. 7 is a partial, enlarged end view of the work handling devices of FIG. 3, as seen from the extrusion gripper receiving side of such devices.

FIG. 8 is an enlarged cross sectional view showing the canoe shaped bumper guards and guides as seen from the section-line VIII—VIII of FIG. 3, looking in the direction of the arrows thereon.

FIG. 9 is an enlarged side plan view of the work gripper mechanism and reset mechanism of this invention showing the work receiving head as just reset for subsequent use and in locked position.

FIG. 10 is similar to FIG. 9 with the exception that the reset mechanism is relocated to show the gripper triggering mechanism in unlocked position.

FIG. 11 is similar to FIGS. 9 and 10 with the exception of showing the work gripping mechanism as actuated.

FIG. 12 is a perspective view of the parts shown by FIGS. 9—11, exclusive of the gripper head.

FIG. 13 is an enlarged side plan view of the upper part of a work carrier device to show the relative relation of the carrier and reset mechanism with respect to certain actuating controls.

FIG. 14 is an enlarged cross sectional end view of the work carriers of this invention, as seen from the section-line XIV—XIV of FIG. 13, looking in the direction of the arrows thereon. This view shows the relative relation of the carrier and reset mechanism with respect to certain control switches.

FIG. 15 is a simple schematic sketch of a control circuit for the motive means for the work carrier device.

FIG. 16 is a perspective view of an alternate gripper control mechanism.

FIG. 17 is a side plan view of the alternate gripper control mechanism shown by FIG. 16.

FIG. 18 is a side elevation view of still another modification of the gripper control mechanism.

FIG. 19 is a cross sectional view of the modified gripper control mechanism as seen from the section-line XIX—XIX of FIG. 18, looking in the direction of the arrows thereon.

FIG. 20 shows a schematic, top plan, view of the grippers of the modified gripper control mechanism of FIG. 19 in a work piece gripping position.

FIG. 21 is a top plan view of an alternate gripper mechanism of the modified gripper control mechanism of FIG. 19, showing an arrangement for gripping two work pieces.

FIG. 22 shows a schematic, top plan, view of the grippers of the alternate gripper mechanism of FIG. 21 in a position gripping the work pieces.

FIG. 23 is a perspective view of a cam follower cylinder which is a part of the modified gripper control mechanisms of FIGS. 18—22.

Referring to the drawings in further detail:

In certain instances the same reference numeral is used to designate separate but identical parts when there are several of these identical parts spaced closely together. This arrangement clarifies the drawings since it avoids crowding a multiplicity of unnecessary reference numerals into a small area.

The metal extruding apparatus includes a press 10 (FIGS. 1 and 2) within which the actual extruding operation is performed. A run-out table 20 is provided at the extrusion gripper receiving side of the press 10. An overhead track arrangement, designated generally as 30, extends over the run-out table 20 between the press 10 and a tower 40 provided beyond the end of the run-out table. A plurality of extrusion handling devices, designated generally as 50, are supported on the overhead track arrangement 30. The extrusion handling devices 50 are adapted to travel separately from the press 10 towards the tower 40 and, in so doing, to guide extrusions received from the press out over the run-out table 20.

The extrusion press 10 includes a housing 11 having a cylindrical passage formed therethrough to receive the billet 12 of material to be extruded and the press ram 13 which provides the extruding force. The housing 11 may receive the billet 12 in a preheated and semi-plastic state by any well known manner. Said housing includes heating means (not shown) to keep the billet in such a pliable state. A die 14, having a given number of die openings 15 (FIGS. 1, 2, and 5) of a certain shape, is located within a support 16 immediately forward of the billet housing 11. The support 16 is usually movable relative to the billet housing 11 to enable the ready exchange of die forms having different extrusion forming openings.

A platen 17 is located forward of the die 14. This platen 17 includes a canister passage within which is disposed an elongated cylindrical member 18 generally referred to as a canister which has a plurality of passages 19 (FIG. 5) formed therethrough. The passages 19 cor-

respond in number to the die openings 15 of a particular die member and are intended to receive and direct the extruded work pieces through the platen 17.

The run-out table 20 is disposed to receive extrusions passing from the canister 18. Accordingly, the height of the run-out table is substantially level with the lower edge of the canister passageways 19. The table includes a flat platform like graphite surface 21 which extends for a considerable length from the press 10. It is desirable to have the run-out table sufficiently long to accommodate the extrusions from a single billet.

The overhead guide track arrangement 30 requires some form of overhead support. Such support may be derived from hangers 31 attached to an overhead beam (not shown) depending from the building roof supports. The hangers 31 are provided at spaced intervals as necessary to maintain guide track members 32 in substantially a horizontal position. A pair of parallel spaced bars 33 and 34 (FIG. 4), separated by threaded bolt and lock unit means 35 and 35a are secured to the hangers 31 and have the guide track brackets 36 secured thereto. The guide tracks 32 are received through the brackets 36 and are held engaged within the brackets by the head end of the bolt means 37 that secures the brackets to the bar 34.

The guide tracks 32 are of inverted channel shaped cross sections with inbent flanges at their open lower sides. A plurality of the guide tracks 32 are secured to the overhead hangers in close parallel relation to afford distinctly separate tracks for different extrusion handling devices designated generally as 50. The number of tracks 32 and devices 50 in use depends upon the number of work pieces that are to be extruded at the same time, as will be shown.

The drive means for the extrusion handling devices 50, as they travel on the guide tracks 32, includes separate drive motors 41, 41a, 41b, 41c, and 41d mounted within the tower 40 (FIGS. 1 and 2). The drive motors 41, 41a, 41b, 41c, and 41d each include a pulley 42, 42a, 42b, 42c and 42d, which drives one of a plurality of axially aligned pulleys 43 upon which wire cables 44 travel. The cables 44 pass over idler pulleys 45 provided on the frame 46 on top of the press 10. The ends of each cable 44 are connected to opposite ends of one 45 of the extrusion handling devices 50.

The extrusion handling devices 50 each include a carriage or trolley portion, designated generally as 60 (FIGS. 1 and 3) having a support frame, designated generally as 70, secured thereto. Work piece gripping mechanisms 50 or gripper devices 80, 80a and 80b are mounted on three of the support frames to provide a three hole arrangement. The other two support frames do not have gripper devices but it should be understood gripper devices can be provided for less or more than three frames providing a one, two, four or five hole arrangement. A gripper resetting mechanism generally designated as 90 is provided within each of the support frames 70 and each frame also includes its own bumper guard and guide means 100, as will be described.

The carriage or trolley 60 of the extrusion handling devices 50 include an elongated bar 61 (FIGS. 3 and 4) having wheeled tracking members 62 that are received within the guide tracks 32 and have their wheels disposed for rolling engagement with the inbent flanges thereof.

The support frames 70 are secured to the trolley or carriage members 60 by means of mounting blocks 66. The mounting blocks, shown in more detail in my co-pending application Serial No. 841,716 entitled "Puller for Extrusion Apparatus" and filed September 23, 1959, 70 now Patent No. 3,058,587, issued October 16, 1962, are of a durable resilient material to afford relatively vibration free and shock resistant support of the frames 70 on the carriers 60.

The support frames 70 comprise a horizontal support member 71 (FIG. 3), of tubular cross section for greater

strength, having guide plates 72 (FIGS. 3, 6, and 13) secured on opposite sides and depending downwardly near one end thereof. A depending frame member 73 (FIGS. 3 and 6) connects a lower disposed support plate 74 to the guide plates 72. The lower support plate 74 in turn is braced by a diagonal brace 75 (FIG. 3) extending upwardly and secured to the forward end of the horizontal support member 71.

The gripper devices, generally 80, 80a, and 80b are best shown in FIGS. 3, 6, 7 and 9-12. FIG. 3 shows each of such devices to be secured to the support plate 74 of frames 70 along the vertically straight sides thereof. FIGS. 6 and 7 show that a selected number of the gripper devices 80, 80a, and 80b are being used whereas blank spaces are left where two additional grippers could be installed. These gripper devices, which are slightly different in configuration and arrangement, are for a 3-hole die.

The gripper devices 80, 80a, and 80b each include a work receiving head 81, 81a and 81b, secured to the support plates 74, 74a, and 74b of the carrier frame 70 by the bars 92, 92a and 92b and bolt and nut assemblies 92'. This arrangement permits the easy removal of the entire gripper device 80 from carrier frame 70 so that different gripper devices can be mounted on the frame for different arrangements required for 1, 2, 3, 4 or 5 hole dies. Control rods 82, 82a and 82b are journaled in rod guides 201, 201a, and 201b for vertical reciprocal movement relative thereto. The rod guides 201, 201a, and 201b are secured to the bars 92, 92a and 92b. The lower ends of rods 82, 82a, and 82b extend downward and have work engaging jaws or feet 83, 83a, and 83b extending into the work receiving members 81, 81a and 81b. In the gripper devices 80, 80b, the rods 82 and 82b are centrally located in the work receiving member, but the feet 83 and 83b are offset from the axis of rods 82 and 82b so that they extend over the extruded strips entering the work receiving members. In the gripper device 80a the rod 82a and foot or jaw 83a is centrally disposed in the work receiving member 81a. Coil springs 84, 84a and 84b are disposed on the control rods 82, 82a and 82b and bear against rod guides 201, 201a and 201b to exert a downward force on collars 85, 85a and 85b fixed to the control rods.

Basically, each gripper mechanism includes the same structure, and as a result only the gripper device 80 will be described in detail. This also applies to the reset mechanism hereinafter to be described.

The work receiving member 81 has a door or gate part 86 (FIGS. 9, 10 and 11), closing one end thereof. An operating lever 87 is secured to the door part and is pivotally connected to the rod collar 85, at its other end. This arrangement is best shown by FIG. 11. The door operating lever 87 is also engaged to the work receiving member 81 by a pivotal link member 88'. A tension spring 89' is engaged between the work receiving member 81 and the operating lever 87, at the connection of the pivotal link 88' thereto. The spring 89' tends to keep the door part 86 closed over the end of the work receiving head 81. When the door member 86 is closed the force of the compression spring 84 acting on the rod collar 85 provides an over-center locking arrangement through the pivotal link 88'.

When an extruded work piece enters the work receiving member 81, and comes into contact with the closed door part 86, it moves the lever 87, which carries the link 88' past the over-center relation and the compression spring 84 drives the gripper jaw down simultaneously as the trap door 86 opens.

The gripper device 80 is operatively connected to a resetting mechanism, designated generally as 90, which is disposed thereover. Each gripper device has a corresponding reset mechanism.

A U-shaped sleeve like member 91 having a slot 91a in the lower portion receives the gripper jaw actuating

rod 82 therewithin. A spacer spring or sleeve 89 is provided on the rod and a pair of lock nuts 89a are secured to the rod. Spring 89 seats on the sides of slot 91a which keeps said spring 89 at all times within sleeve 91 as is clear from FIGS. 9-12. Thus, the member 91 is reciprocal relative to the rod 82 within the distance available between the end of the spacer spring 89, when engaged with the lock nuts 89a, and the fixed guide bar 201. The entire gripper device 80 when detached from plate 74 is removable from member 91 by merely sliding the upper end out of the space between the sides of member. In so doing rod 82 slides in slot 91a.

A guide follower roller 93 is mounted at the upper end of the sleeve like member 91 between its sides. This roller is intended to ride upon a horizontally reciprocal cam surface of the reset mechanism 90.

The reset mechanism 90 includes a pair of bar or rod members 94 and 95, termed top and bottom, respectively, disposed horizontally and with their axes lying in a vertical plane. The top bar 94 is bent downwardly and interconnected with a straight portion of the bar 95 in overlapping relationship. The bottom bar 95 is bent upwardly and secured to a straight portion of the top bar 94. This results in a member of trapezoidal configuration. One short side of the trapezoid forms a cam shoulder 96 on the uppermost bar 94 which is intended to lift the sleeve like member 91 by means of the guide follower roller 93 thereof as it rides thereover.

The interconnected rods 94 and 95 are guided for horizontal movement by a roller 97 mounted between the carrier frame plates 72 and a hanging guide 98 depending from the carrier frame member 71 (FIG. 3).

Small collar guide buttons 99 are provided on the outside of the shaft that supports the guide following roller 93, at the upper end of the member 91. These guide buttons are received between the edge of the carrier frame plates 72 and the edge of a guide plate 99' secured to the frame member 71 for the express purpose of forming a vertical guide slot for such buttons. Accordingly, as the interconnected rod members 94 and 95 are reciprocated back and forth, the sleeve like part 91 is raised and lowered due to the travel of the roller 93 over the cam shoulder 96 and the restraint against other than vertical travel imposed by the guide slot forming parts 72 and 99'.

Referring now to the sequence of operational positions of the gripper and resetting mechanisms 80 and 90, shown by FIGS. 9-11:

When the roller 93 rides over the cam shoulder 96, the U-shaped member 91 moves the spacer sleeve 89 upward. The spacer sleeve 89 engages the lock nuts 89a causing the gripper rod 82 to be lifted. This in turn raises the gripper jaw 83 and closes the door 86 over the end of the work receiving housing 81.

The return of the roller 93 to the bottom of the cam shoulder 96, as in FIG. 10, will not affect the gripper mechanism due to the free travel afforded the end of the sleeve like member 91 between the lock nuts 89a and the control rod 82. However, should a work piece engage the trap door 86, the gripper is triggered and the rod 82 moves the jaw part 83 into engagement with such work piece.

In the course of travel of the carriers 50, along table 20, they are guided relative to each other by the canoe shaped guards 100 (FIGS. 2, 3, and 8) attached to the respective carriers. The use of such guide and guard means for the carriers in transit and for orienting the work receiving heads 81 at the press, is best described in our copending patent application S.N. 841,720 entitled, "Extrusion Puller Equipment," and filed September 23, 1959. In brief, the canoe shaped guards are formed by elongated members 101 and 102 secured horizontally on each side of the carrier to brace 75 and frame member 73 by brackets 75' and 73' respectively, and converging together at their ends. This enables them to guide the carriers, as shown by FIG.

8, and even when one carrier lags or advances beyond another. Their converging or tapered ends assist in nesting the carriers together, at the press, within guides 47 mounted on frame 46. Also provided for positioning the carriers at the press is the plate 47a which has V-shaped cut out portions for receiving the tapered V-shaped ends of the canoes as shown by FIG. 2.

At the end travel positions for the carriers 50, stops 103, which are adjustable along the guide tracks, and fixed stops 104 are located for engagement and actuation of the reset mechanism 90. Stop 103 is mounted on the guide tracks 30 near the end of the run-out table 20, as best shown by FIG. 1. Stop 104 is mounted on the housing part 46 on top of the extruding press 10.

The end of rod 94 engages stop 103 as the carrier approaches the end of the run-out table 20. This causes the reset mechanism 90 to be moved relative to the carrier and the roller 93 to be raised on the cam shoulder 96. As the sleeve like housing 91 is raised it engages the spacer sleeve 89 and raises it into lifting engagement with the lock nuts 89a on the gripper control rod 82. As the control rod 82 is lifted, the gripper jaw 83 is released from the work piece and the rod collar 85 causes the door lever 87 to close the door or gate part 86, with the assistance of the tension spring 89. As mentioned, the operating link 88 is arranged to provide an over-center locking condition when the door or gate 86 is closed over the end of the work receiving housing.

The reset mechanisms 90 have their rod parts 94 projecting outward towards the press 10 during the return travel of the carriers 50. As they approach the press 10, the rods 94 engage stops 104. The reset mechanisms are stopped and the carriers 50 over run the reset mechanism and allow the rollers 93 to return to the bottom of the cam shoulder 96. This movement does not immediately affect the gripper devices 80 other than to cause them to be left in a readily triggerable disposition; as shown by FIG. 10.

When a work piece W enters the receiving housing part 81 and engages the door part 86, as in FIG. 10, the mechanism is triggered and the gripping jaw is moved into work holding position.

The control rod part 82 includes a control switch actuating member 105 at its upper end. The switch actuating member is guided within the confines of the sleeve like member 91 for vertical reciprocal movement with the control rod 82. Accordingly, when the gripper mechanism 80 is tripped, upon receipt of a work piece, the switch actuating member is moved downwardly and, as shown by FIG. 13, contacts and actuates a control switch 106. The arrangement of control switches 106 and actuators 105, for the different carriers 50, is best shown by FIGS. 3 and 13.

The control switches 106 are connected to the carrier drive motors 41, 41a, etc. as shown schematically by FIG. 14, to effect energization or clutching thereof and initiation of the carrier operation.

Switch members 107 may be mounted on the end stops 103, as shown by FIG. 1, for engagement by the end of the carrier guides 93 at the run-out position. Such switches are connected to the drive motors 41, 41a, etc. as are switches 106, to effect a reversal of their drive direction and a return of the carriers 50 to their original positions near the extruding press 10. Other switch means 108, also connected to the drive motors 41, 41a, etc. as are switches 106 and 107, are disposed near the extruding press 10 for engagement by end flanges 109 on the carrier frames 70, when the carriers are nested together at the press. These switches 108 also affect a reversal of the drive direction of motors 41, 41a, etc. so that they are ready to operate in the right direction when the cycle is again initiated by the switch means 106.

To coordinate the return of the handling devices 50, a retarder gate 110 is provided as shown by FIG. 7. The retarder gate is a pivotal bar 111 mounted on one of the

handling devices 50 and adapted to assume either a non-interfering vertical position or an overlapping horizontal relation to the other handling devices. This is best shown by FIG. 7. Automatic or manual means may be used to dispose the bar 111 in a horizontal position at the start of, or at some determinative position during, its return travel. The handling device which includes the retarder gate is set to have a slower return rate than the other devices. Accordingly, the other devices will come into alignment with the slower device during the return travel and all will be aligned upon approaching the extrusion press 10.

Operation

The electrical controls for this invention are not an integral part of this invention so no illustration or detailed explanation is considered necessary. However, for a complete description of such controls, and their interrelation with other mechanism mentioned, reference should be made to our copending application S.N. 841,800, filed September 23, 1958, and entitled "Method and Control Apparatus for Pulling Extrusions From Dies."

The number of work handling devices 50 to be used for an extrusion operation is dependent upon the die form 14 that is used. A separate work handling device is to be used for each opening in the die 14.

The work handling devices 50 are mounted on the guide track arrangement 30, in the manner mentioned. The selected die 14 is mounted in the support 16. The proper canister 18, with the required passages for the selected die, is mounted in the housing 17 forward of the die. The press is thereafter placed in operation and the press ram acts against the end of the billet to cause the extrusion of metal through the die.

The extruded work pieces are received through the canister passage 19, from the die 14, and are directed towards the run-out table 20. The work pieces pass into funnel members 88, 88a, and 88b which are a part of the work receiving housings 81, 81a, and 81b. The funnel guidance arrangement is best disclosed in our copending patent application S.N. 841,720, entitled, "Extrusion Puller Equipment," and filed September 23, 1959. When an extruded piece W engages the door or gate 86 the clamping mechanism is triggered into operation. As the clamping rod 82 drops, under pressure of spring 84, the drive motor switch actuating member 105 activates switch 106 and starts the carrier drive motor 41.

The handling devices 50 travel at a moderate rate dictated by the flow of metal through the extrusion die 14. Only very slight pulleying pressure is applied. During the run-out operation, over table 20, the shock mounts 66 afford substantially complete vibration and shock isolation between the work carrying or supporting frames 70 and the trolleys 60. The bumper guards 109 keep the handling devices 50 laterally spaced.

As the handling devices 50 approach the end of their travel, the gripper resetting mechanism 90 engages the stop 103 near the end of the track system 30. The interconnected rods 94 and 95 are moved relatively within the support frame 70 and the gripper devices 80 are released from engagement with the work and are reset for subsequent operation. Continued travel of the work devices 50 causes the hanging support bracket 98 of the frame 70, at the forward end thereof, to engage the drive motor control switch 107. The switches 107 effect a reversal of the direction of drive within the drive motors 41, 41a, 41b, 41c and 41d so that the handling devices 50 are readied for their return travel to the die 10.

After the extruded work pieces are removed from the work receiving members 81, 81a and 81b as by removal through an open side thereof, or other means, the handling devices 81, 81a and 81b are ready to be returned to the press 10. The return travel is much more rapid than the forward travel. However, as mentioned, one of the drive motors 41, 41a, 41b, 41c and 41d is set to

return its handling device 50 slower than the others. It is this handling device which includes the retarder gate 110. The retarder gate 110, in its horizontal position, keeps all of the handling devices laterally aligned so that they approach the press 10 together. The bumper guards 100 again serve to maintain the proper relative lateral spacing of the handling devices. They also serve to prevent them from weaving in and out during their relatively rapid return stroke.

As the handling devices 50 approach the press 10 the reset mechanisms 90 are themselves reset for operation by engagement with the stops 104. The switch actuators 105 for the drive motors 41, 41a, 41b, 41c, and 41d on the gripper jaw control rods 82, 82a and 82b have been previously repositioned in reloading the gripper mechanisms 80, 80a, and 80b. Accordingly, they are in position to inactivate the drive motors 41, 41a, 41b, 41c, and 41d when the handling devices 50 are back in their starting positions.

The different handling devices 50 are further assured of being properly positioned, upon their return, by the stationary guides 47 and 47a. The convergent use of the outermost guards 100 of the handling devices co-operate with the fixed guides 47 and 47a to cause each of the handling devices to nest properly at the extrusion receiving end of press 10 ready for another run.

Modifications

An alternate form of gripper control mechanism is shown by FIGS. 16 and 17.

The gripper mechanism 180 is secured to the carrier frame 70 by welding or any other suitable manner. The gripper housing 181 which is a U-shaped member turned on its side, is secured to the lower end of the support member 192 by bolts (not shown). The housing 181 is open at its front and rear ends. A rod 182 extends through the top plate of the housing and has secured on its bottom end a clamping plate or jaw 183. Its upper end is slidably mounted in the bearing 184a fixed to support 192. The rod and clamping plate are biased downwardly by means of the linkage arm 145, lever 147 and spring 184.

A releasable trigger means is provided for normally locking the clamping rod 182 and clamping plate 183 upwardly. This trigger means includes the pivoted gate or trigger 186 pivotally mounted to the back end of the housing 181. This gate 186, when closed, covers the entire back opening of the housing whereby when an extruded strip enters the housing and passes therethrough it must by necessity strike it. Gate 186 is normally held closed by the over center toggle linkage 187 which includes the links 187a and 187b pivotally connected together at the knee 188. Link 187a is pivotally connected at its opposite end to the block 185. The link 187b, which comprises two pieces pivotally attached to each side of link 187a is pivotally connected at its other end to the bar 189 which is secured to and extends upwardly from gate 186. A stop member 109 extends upwardly from the housing 181 providing means that prevents the knee 188 from entirely collapsing inwardly toward rod 182. It also provides a pivot point about which the link 187b pivots when the gate 186 is swung upwardly. The toggle linkage 187 is arranged so that when the gate is swung downwardly the two links 187a and 187b are slightly over center and locked in that position. In this position (FIG. 17) the force exerted by the spring 184 through lever 147 and link 146 is incapable of forcing the rod 182 and clamping plate 183 downwardly. However, when the gate 186 is pivoted upwardly the link 187b in pivoting about the point of contact with stop member 109 breaks the knee joint 188 outwardly in a direction away from rod 182. This eliminates the locking effect of toggle linkage 187 and permits the rod and clamping plate to be forced downwardly by the spring 184. A spring 189' is provided for positively holding the gate 186 open by the force applied through link 187b.

A micro-switch 160 is mounted on the frame at a point where it is actuated by the joint between the lever 146 and link 147. In the position of FIG. 17, this switch is open; however, when the gripper device is triggered the lever 146 and link 147 move out of engagement with the switch 160 closing its contacts and energizing one of the pull motors such as motor 41a. In this respect the switch 160 serves the same purpose as switch 106 (FIGS. 3 and 13).

10 In this modification the work piece W is released from the gripper jaw, upon the extrusion handling device reaching the far end of the run-out table, by grasping the lever 147 and manually raising the jaw 83. The trigger mechanism 187 is also reset during the same manual releasing operation.

15 FIGS. 18-22 show other modifications of gripper devices. Two modifications are shown in these figures; however, they basically have the same structure. The only difference is that FIGS. 18-20 show a gripper device for a single hole die and FIGS. 21-23 show a similar type device for a two hole die.

20 Referring to FIGS. 18-19 and 20, reference numeral 280 designates the over-all gripper device which is arranged to be mounted on the plates 74 previously described. This gripper device 280 includes the two upright supports 290a and 290b having the openings 291a and 291b, respectively, for attaching the bars and supporting the units on the plates 74 (FIGS. 9-12) of the frames previously described.

25 30 Each of these supports 290a and 290b have a guide collar 281a at their upper ends. Attached to the lower ends of the bars is the rectangular support plate 292 which spans the distance between the two bars 290a and 290b and extends forwardly and rearwardly thereof. The support plate 292 supports two guide blocks such as designated by 293a aligned with the guide collar 281a. The guide collar and guide block have openings 289a and 294a, respectively, vertically aligned with each other and receiving the actuating rod 282a. Actuating rod 282b is received by similar openings (not shown). These two actuating rods 282a and 282b are adapted (but not shown) to be connected to the resetting mechanism such as 90 of FIGS. 9-12. Secured to the rods 282a and 282b are the operating or actuating collars 285a and 285b which are located between the guide collars and guide blocks. The spring 284a is located between the guide collar 281a and the operating collar 285a. Similarly, spring 284b is located between its guide collar (not shown) and actuating collar 285b. These springs serve the function of biasing the actuating rod downwardly which in turn moves the operating collars 285a and 285b downwardly for actuating the clamping jaws 283a and 283b which will now be described.

35 40 45 The two jaws 283a and 283b are substantially identical and comprise a semi-circular member having the serrations or teeth 309a and 309b, respectively. The clamping jaws are connected to the shafts 307a and 307b extending through and below the support plate 292 and extending upwardly to the bearing plate 295. The shafts 307a and 307b are supported by the bearing plate 295 which in turn is supported on the bearing supports 296a and 296b attached to the support bars 290a and 290b, respectively. The top end of the shaft 307a or 307b has a reduced portion extending through the opening 298a of the bearing plate 295. Bolt and nut assemblies 308a and 308b, one for each of the shafts, rotatably support the shafts on the bearing plate 295. At their lower ends, immediately above the plate 292, the shafts 307a and 307b are journaled in openings such as opening 299a of the bearing block 297a.

50 55 60 65 70 Between the bearing plates 295 and the bearing blocks are located the cam follower cylinders 300a and 300b, the structure of which is shown in more detail by FIG. 23. Cylinder 300a, which is identical to cylinder 300b, consists of an arcuate plate 301a bent into a semi-circular

shape and having secured in its ends plugs 302a and 303a. These plugs have aligned openings such as 305a, through which the shaft 307a extends. The shaft 307a is keyed to the cam follower cylinder 300a so that it is rotatable therewith. The member 301b is an arcuate plate which is the mirror image of member 301a.

The arcuate shaped plate or wall 301a has an elongated cam opening 304a receiving a cam roller 310a attached to the end of the actuating collar 285a by the shaft 311a. Similarly, the cam follower cylinder 300b has a cam opening 304b receiving the cam roller 310b supported by the shaft 311b supported on the actuating collar 285b. It should be obvious from this description and the drawings that as the operating collars 285a and 285b reciprocate, the rollers 310a and 310b ride in the cam openings 304a and 304b causing the cam follower cylinders 300a and 300b to rotate which in turn rotates the clamping jaws 283a and 283b. This action occurs as the springs such as spring 284a bias and push the operating collars such as collar 285a downwardly.

A trigger mechanism is provided, such mechanism being very similar to that previously described. It consists of a trigger gate 286 pivotally mounted behind the clamping jaws 283a and 283b as illustrated by FIGS. 18 and 19. The trigger gate 286 is secured to the pivotally mounted operating levers 287a and 287b which in turn are pivotally secured at their top ends to the operating collars 285a and 285b, respectively. Pivotal link members 288a and 288b are pivotally secured to each of the blocks such as 293a, also to the operating lever 287a and 287b. These pivotal connections are such that the pivotal center points such as points 312a, 313a and 314a lie substantially on a common line. As shown by FIG. 18 the pivotal point 313a is located slightly to the left of a line between the two points 312a and 314a thus providing an over-center type arrangement which prevents the spring 284a from pushing the operating collar 285a downwardly. However, if this link is broken so that the center point 313a is located to the right of the line between the two points 312a and 314a, the spring 284a will push the operating collar 285a downwardly as the gate 286 swings upwardly as shown by the phantom lines.

It should be understood that FIG. 19 shows the position of the jaws open and also shows all the structure through the cross-section line XIX—XIX while FIG. 20 is only a schematic diagram showing the position of the clamping jaws in gripping position. It will be noted that the arrangement of these clamping jaws is such that they will accommodate any size extrusion strip such as strip S₃.

FIGS. 21 and 22 show a very similar type of structure. The main difference is that this structure is divided into two separate sections, each one arranged to grip a single strip thus providing a two hole gripper mechanism. It will be noted that the gripper device 380a includes the support bar 390a having the openings 391a for supporting the bar on a plate such as 74 in FIGS. 9-12. Reciprocally mounted on this support 390a is the actuating rod 382a carrying the operating collar 385a which is adapted to be pushed downwardly by the spring 384a. On the end of the operating collar 385a is mounted the cam roller 410a by means of the shaft 411a. This cam roller rides in a slot of the cam follower cylinder 400a so that as the operating collar 385a is pushed downwardly or is lifted upwardly the cam follower cylinder rotates, which in turn rotates the shaft 407a on the end of which is the clamping jaw 383a. The jaw 383a has a serrated surface 409b which rotates toward the cooperating gripper plate 412a to grip an extruded strip S₄ therebetween.

The cam follower cylinder which consists of the arcuate shaped plate or wall 401a having the plugs 402a on each end is mounted below the bearing plate 395a which in turn is supported by the bearing support 396a. The shaft 407a is secured against vertical movement by the nut assembly 408a.

This gripper device has a similar trigger arrangement

to that previously described which includes the trigger gate 386a, the operating lever 387a, and the pivotal link members 388a.

The gripper device 380b located to the right in FIG. 21 is substantially identical to the gripper device 380a. It includes the support bar 390b, the actuating rod 382b, the clamping jaw 383b, gripper plate 412b, spring 384b, and the operating collar 385b. It also has the cam operating mechanism including the cam roller 410b mounted on the end of the operating collar 385b by the shaft 411b. This cam roller rides in a slot provided in the cam follower cylinder 400b which includes the arcuate shaped plate 401b having the end plugs 402b receiving the shaft 407b. The shaft 407b is secured against vertical movement by the nut assembly 408b. The cam follower cylinder is mounted between the bearing plate 395b and a bearing block (not shown). The bearing plate is supported by a bearing support 396b.

The clamping jaw 383b having a serrated surface or teeth 409b is triggered by the trigger mechanism which includes the trigger gate 386b, the operating lever 387b, and the pivotal link members 388b.

The gripper device 380b operates exactly like the gripper device 380a. The extruded strip passing into the front of the gripper device strikes the trigger gate 386b which triggers the device causing the jaw 383b to rotate and clamp strip S₅ between it and the gripper plate 412b (FIG. 22). It should be understood that FIG. 21 shows the details whereas FIG. 22 shows a schematic of the device in gripping position.

In order to keep the two devices 280a and 280b separated, the runners 413a and 413b, inclined away from each other at their front ends, are provided. This permits the two devices to slide past each other.

It should be understood that the gripper devices of FIGS. 18-23 are utilized in the apparatus previously described. These figures show only a variation or modification of the means for gripping the extruded strip although the triggering means is substantially identical.

Although this invention has been described in detail and illustrated in various forms, it should be understood that alterations and modifications are possible within the spirit of this invention. As a result this invention is to be limited only as set forth by the express language of the appended claims.

We claim:

1. Work receiving apparatus for use with attenuated moving work comprising; a run-out table; support means adapted for reciprocal travel throughout substantially the length of said run-out table; a work receiving head provided in work receiving relation on said support means adjacent one end of said table; a work engaging jaw member operable within said work receiving head, an over-center mounted trigger mechanism operatively connected to said work engaging jaw and disposed for engagement and activation by an end of said attenuated work moving in said work receiving head for actuating said jaw for gripping the work; and cam means carried by said support and operatively engaged with said jaw member for the retraction thereof from work engagement and the resetting of said trigger mechanism, said cam means including a cam member reciprocal in the direction of the run-out table and having surfaces of varying levels, a cam follower means riding on said surfaces and connected to said jaw member; and means located adjacent the other end of said table and in the path of said support means for actuating said cam member in one direction along said run-out table causing said cam follower to ride from a surface at one level to a surface at another level thereby moving said jaw member to retracted position.

2. Work receiving apparatus for use with attenuated moving work comprising; a run-out table; support means adapted for reciprocal travel throughout substantially the length of said run-out table; a work receiving head provided in work receiving relation on said support means

adjacent one end of said table; a work engaging jaw member operable within said work receiving head, an over-center mounted trigger mechanism operatively connected to said work engaging jaw and disposed for engagement and activation by an end of said attenuated work moving in said work receiving head for actuating said jaw for gripping the work; and cam means carried by said support and operatively engaged with said jaw member for the retraction thereof from work engagement and the resetting of said trigger mechanism, said cam means including a cam member reciprocal in the direction of the run-out table and having surfaces of varying levels, a cam follower means riding on said surfaces and connected to said jaw member; means located adjacent the other end of said table and in the path of said support means for actuating said cam member in one direction along said run-out table causing said cam follower to ride from a surface at one level to a surface at another level thereby moving said jaw member to retracted position; and means located adjacent the said one end of said table in the path of said support means for engaging said cam member causing it to move in an opposite direction along said run-out table and said cam follower to ride from the surface of higher level to a surface of lower level thereby permitting the jaw member to be released by said trigger mechanism.

3. Work receiving apparatus for use with attenuated moving work comprising; a run-out table; support means adapted for reciprocal travel throughout substantially the length of said run-out table; a work receiving head provided in work receiving relation on said support means when adjacent one end of said table; said head having a lower clamping surface; a work engaging jaw member mounted for reciprocation within said head above said clamping surface for clamping said work between said jaw and clamping surface; a rod extending upwardly from said jaw member; spring means biasing said rod and jaw member downwardly into clamping position; a trigger means pivotally mounted over the outlet to said work receiving head for engagement by said attenuated moving work as it moves through said head; and a link means operatively connected to said trigger means and rod for restraining the rod and jaw members from clamping when said trigger is in one position and for releasing said rod and jaw member in another position of said trigger, 45 said link means and said trigger means including an over-

center toggle having a knee that breaks from one side of center to the other side of center and on said one side said trigger means is in cocked position with the rod and jaw member in an up position restrained from moving downwardly while on the other side said trigger means is in uncocked position permitting the rod and jaw member to move downwardly whereby said trigger means can be easily recocked by merely moving said rod into up position.

5 10 15 20 25 30 40 45

4. Work receiving apparatus for use with attenuated moving work comprising; a run-out table; support means adapted for reciprocal travel throughout substantially the length of said run-out table; a work receiving head provided in work receiving relation on said support means when adjacent one end of said table; a work engaging jaw member operable within said work receiving head; said jaw member being rotatable from a non-clamping position to a clamping position; a reciprocal rod having a first cam member attached thereto; a second cam member attached to said rotatable jaw member and cooperating with said first cam member whereby reciprocation of said rod rotates said jaw member; spring means for biasing said rod in one axial direction for rotating said jaw member to clamping position; releasable restraining means resisting the bias of said spring for holding said jaw member in non-clamping position; and a trigger means operatively connected to said restraining means for releasing said restraining means in response to the moving of said attenuated work into said work receiving head against said trigger means.
